UNITED STATES PATENT OFFICE.

ERIC MICHAEL DE SHERBININ, OF TORONTO, ONTARIO, CANADA, ASSIGNOR, BY MESNE ASSIGNMENTS, TO PARAGON DISHWASHER SYNDICATE INCORPORATED, A CORPORATION OF NEW YORK.

CABINET.

Application filed June 25, 1923. Serial No. 647,707.

To all whom it may concern:

Be it known that I, ERIC MICHAEL DE SHERBININ, a British subject, residing at the city of Toronto, in the county of York and 5 Province of Ontario, Dominion of Canada, have invented certain new and useful Improvements in Cabinets; and I hereby declare that the following is a full, clear, and exact description of the same.

10 My invention relates to the construction of a splash proof cabinet in which one or more streams of water are discharged under pressure against its contents and which is formed with an opening for access to its interior 15 closed by a sliding sash door that will prevent the discharge finding an outlet through the opening or around its edges.

The preferred type of door comprises a substantially rectangular frame consisting 20 of two spaced vertical members each having a double rabbet adjacent to and parallel with its inner edge and two spaced horizontal members located one at the top and the other near the bottom of, and integral with, the 25 vertical members and in the same plane as the vertical parts of the inner rabbets. The panel contacts the inner rabbets and the surfaces of the horizontal members adjacent to their inner edges and this panel is held in 30 position by panel holding members, attached in the outer rabbets, overlying the side edges of the panel and having panel supports at their lower ends engaging its bottom edge, and by a cross piece contacting the inner 35 surfaces of the outer rabbets, extending between the vertical members, and covering the top edge of the panel and having an out-turned offset extending to the top horizontal member.

40 One or more spacers may be inserted between this cross piece and the top horizontal member above the top edge of the panel to hold them in spaced relation for the entry of the panel between them which is preferably transparent and removable and replaceable.

The inner surface of the frame is provided 50 with a rabbet at its lower edge to fill the gap or space at the bottom of the lower horizontal member between the lower ends of the vertical members and this rabbet has a vertical wall extending upward to, and contacting, the lower horizontal strip between the inner rabbets. Inserted between the bottom

of the panel and the top of the lower horizontal member is an apron having its bottom edge seated in the bottom rabbet. 55

In the drawings:

Fig. 1 is an elevational view of a door constructed in accordance with this invention, 60

Fig. 2 is a vertical section on the line 2—2 Fig. 1,

Fig. 3 is a transverse section on the line 3—3 Fig. 1, 65

Fig. 4 is a transverse section on the line 4—4 Fig. 1,

Fig. 5 is an elevational view of the door frame,

Fig. 6 is an end elevational view of the top cross piece, 70

Fig. 7 is an edge elevational view of one of the panel supports, and

Fig. 8 is an elevational view of the bottom rabbeted member. 75

Like characters of reference refer to like parts throughout the specification and drawings.

The door consists of a substantially rectangular frame composed of two spaced parallel vertical members 1 formed with inner and outer rabbets 2 and 3, respectively along their inner edges and two spaced horizontal members 4, 5 located one at the top and the other at the bottom of the vertical members 80 extending between, and in the same vertical plane as, the inner rabbets 2. The door is preferably constructed of metal and the vertical horizontal members are integral with the vertical members. The panel 6 which 85 is preferably of glass, contacts the inner surfaces of the inner rabbets 2 and the inner surfaces of the top and lower horizontal members 4 and 5 adjacent to their inner edges. Seated in the outer rabbets 3, and secured to the frame, is a cross piece 7 parallel to and corresponding in depth to the top horizontal member 4, and this cross piece 90 overlies the upper part of the panel 6 and covers its top edge. The top edge of the cross piece 7 is formed with an out-turned offset 8 which contacts the inner surface of the top edge of the top horizontal member 4, and interposed between the cross piece 7 and the top horizontal member 4 is a spacer 9 100 placed slightly above the top edge of the panel 6. Seated in, and parallel with, the outer rabbets 3 are panel holding members

105

10 secured at their upper ends to the frame and having at their lower ends panel supports 11 which engage the bottom edge of the panel 6. The top edges of the panel holding members 10 are in contact with the bottom edge of the cross piece 7 and the panel supports 11 are slightly below the top edge of the bottom horizontal member 5. The lower ends of the panel holding members 10 are free to move a limited distance from the outer rabbets 3 for the removal and replacement of the panel so that in the event of damage to the panel it can be removed and replaced by another without the door having to be taken apart. The width of the panel holding members 10 is equal to the combined width of the inner and outer rabbets 2 and 3; this being sufficient to provide the panel holding members with a contacting surface which completely covers the side edges of the panel.

Secured to the bottom of the frame is a cross piece 12 contacting the lower horizontal member near its bottom edge and extending between the inner rabbets 2. The lower part of the cross piece 12 is formed with a rabbet 13 extending to its lower edge and the length of this rabbet is equal to the distance between the outer rabbets 3. Inserted between the panel 6 and the bottom horizontal member 5 is the upper edge of the apron 14. The bottom edge of this apron is slightly above the bottom rabbet 13 and extends across the space between the inner rabbets 2 to cover the top edge of the cross piece 12 and prevent a leakage from the interior of the cabinet between the cross piece and bottom horizontal member 5.

40 Fastened to the vertical members near their side edges are guide pieces 18 extending from the top to the bottom of the door and beyond these guide pieces the vertical members are entered in channelled slide-ways 20 formed in the vertical sides of the door opening 21. These slideways are so located that the vertical and bottom edges of the door are within the plane of the cabinet front. With this construction the water striking against the interior of the door and the cabinet front drains from the top interiorly of the door downwardly past the bottom edge of the door opening, and the slides and slide-ways prevent the water finding an outlet between the vertical sides of the door and the vertical sides of the opening.

Having thus fully described my invention, what I claim as new and desire to secure by Letters Patent is:—

1. In a cabinet, a sliding sash door comprising two spaced vertical members each having a double rabbet adjacent to and parallel with its inner edge, two spaced horizontal members located one at the top and

the other near the bottom of, and integral with, the vertical members and in the same plane as the vertical surfaces of the inner rabbets, a rabbet at the bottom of the lower one of the horizontal members extending to, and in the same plane as the bottom of the vertical members, a panel contacting the surfaces of the inner rabbets and the surfaces of the horizontal members adjacent to their inner edges, panel holding members secured in the outer rabbets overlying the side edges of the panel and having panel supports at their lower ends engaging the bottom edge of the panel, and a cross piece, contacting the inner surfaces of the outer rabbets, extending between the vertical members and covering the top edge of the panel.

2. In a cabinet, a sliding sash door comprising two spaced vertical members each having a double rabbet adjacent to and parallel with its inner edge, two spaced horizontal members located one at the top and the other near the bottom of, and integral with, the vertical members and in the same plane as the vertical surfaces of the inner rabbets, a rabbet at the bottom of the lower one of the horizontal members extending to, and in the same plane as the bottom of, the vertical members, a panel contacting the surfaces of the inner rabbets and the surfaces of the horizontal members adjacent to their inner edges, panel holding members secured in the outer rabbets overlying the side edges of the panel and having panel supports at their lower ends engaging the bottom edge of the panel, a cross piece, contacting the inner surfaces of the outer rabbets, extending between the vertical members covering the top edge of the panel and having an out-turned offset extending to the top horizontal member.

3. In a cabinet, a sliding sash door comprising two spaced vertical members each having a double rabbet adjacent to and parallel with its inner edge, two spaced horizontal members located one at the top and the other near the bottom of, and integral with, the vertical members and in the same plane as the vertical surfaces of the inner rabbets, a rabbet at the bottom of the lower one of the horizontal members extending to, and in the same plane as the bottom of, the vertical members, a panel contacting the surfaces of the inner rabbets and the surfaces of the horizontal members adjacent to their inner edges, panel holding members secured in the outer rabbets overlying the side edges of the panel and having panel supports at their lower ends engaging the bottom edge of the panel, a cross piece contacting the inner surface of the outer rabbets, extending between the vertical members covering the top edge of the panel and having an out-turned offset extending to the top horizontal member, and a spacer

inserted between the cross piece and top horizontal member above the top edge of the panel.

4. In a cabinet, a sliding sash door comprising two spaced vertical members each having a double rabbet adjacent to its inner edge, two spaced horizontal members located one at the top and the other at the bottom of, and integral with, the vertical members and in the same plane as the vertical surfaces of the inner rabbets, a cross piece extending between the vertical members near their lower ends covering the bottom edge of the lower one of the horizontal members and having at its bottom edge a rabbet in the same plane as the vertical members, a panel contacting the surfaces of the inner rabbets and the surfaces of the horizontal members adjacent to their inner edges, panel holding members secured in the outer rabbets overlying the side edges of the panels and having panel supports at their lower ends engaging the bottom edge of the panel, a cross piece contacting the inner surfaces of the outer rabbets, extending between the vertical members covering the top of the panel, and an apron inserted between the panel and lower horizontal members having its bottom edge seated on the rabbet of the cross piece and extending between the inner rabbets of the vertical members.
5. In a cabinet, a sliding sash door comprising two spaced vertical members each having a double rabbet adjacent to its inner edge, two spaced horizontal members located one at the top and the other at the bottom of and integral with the vertical members and in the same plane as the vertical surfaces of the inner rabbets, a cross piece extending between the vertical members near their lower ends covering the bottom edge of the lower one of the horizontal members and having at its bottom edge a rabbet in the same plane as the vertical members, a panel contacting the surfaces of the inner rabbets and the surfaces of the horizontal members adjacent to their inner edges, panel holding members secured in the outer rabbets overlying the side edges of the panels and having panel supports at their lower ends engaging the bottom edge of the panel, a cross piece, contacting the inner surfaces of the outer rabbets, extending between the vertical members covering the top of the panel, an apron inserted between the panel and lower horizontal members having its bottom edge seated on the rabbet of the cross piece and extending between the inner rabbets of the vertical members.
6. In a cabinet, a sliding sash door comprising two spaced vertical members each having a double rabbet adjacent to its inner edge, two spaced horizontal members located one at the top and the other at the bottom of and integral with the vertical members and in the same plane as the vertical surfaces of the inner rabbets, a cross piece extending between the vertical members near their lower ends covering the bottom edge of the lower one of the horizontal members and having at its bottom edge a rabbet in the same plane as the vertical members, a panel contacting the surfaces of the inner rabbets and the surfaces of the horizontal members adjacent to their inner edges, panel holding members secured in the outer rabbets overlying the side edges of the panels and having panel supports at their lower ends engaging the bottom edge of the panel, a cross piece, contacting the inner surfaces of the outer rabbets, extending between the vertical members covering the top of the panel, an apron covering the bottom edge of the panel seated on the rabbet of the cross piece and extending between the inner rabbets of the vertical members, a spacer between the top horizontal member and cross piece, and an outwardly turned off-set at the top edge of the top cross piece engaging the top horizontal member.

lower ends engaging the bottom edge of the panel, a cross piece, contacting the inner surfaces of the outer rabbets, extending between the vertical members covering the top of the panel, an apron inserted between the panel and lower horizontal members having its bottom edge seated on the rabbet of the cross piece and extending between the inner rabbets of the vertical members, and a spacer between the top horizontal member and cross piece.

6. In a cabinet, a sliding sash door comprising two spaced vertical members each having a double rabbet adjacent to its inner edge, two spaced horizontal members located one at the top and the other at the bottom of and integral with the vertical members and in the same plane as the vertical surfaces of the inner rabbets, a cross piece extending between the vertical members near their lower ends covering the bottom edge of the lower one of the horizontal members and having at its bottom edge a rabbet in the same plane as the vertical members, a panel contacting the surfaces of the inner rabbets and the surfaces of the horizontal members adjacent to their inner edges, panel holding members secured in the outer rabbets overlying the side edges of the panels and having panel supports at their lower ends engaging the bottom edge of the panel, a cross piece, contacting the inner surfaces of the outer rabbets, extending between the vertical members covering the top of the panel, an apron covering the bottom edge of the panel seated on the rabbet of the cross piece and extending between the inner rabbets of the vertical members, a spacer between the top horizontal member and cross piece, and an outwardly turned off-set at the top edge of the top cross piece engaging the top horizontal member.

Dated at the said city of Toronto, this 30th day of May, A. D. 1923.
